[57] CLAIM

The ornamental design for a pen and pencil holder for
automobile visor or similar article, substantially as
shown and described.

DESCRIPTION

FIG. 1 is a perspective view of a pen and pencil holder
for automobile visor or similar article, showing my new
design;

FIG. 2 is a top plan view thereof;

FIG. 3 is a front elevational view thereof;

FIG. 4 is a right side elevational view thereof, the side
opposite being substantially a mirror image;

FIG. 5 is a rear elevational view thereof; and,

FIG. 6 is a bottom plan view thereof.

The broken line showing of an automobile visor and pen
in FIG. 1 is for illustrative purposes only and forms no
part of the claimed design.
